SHOE PRESS

John Frederick Smith, Quincy, Mass., assignor
to Compo Shoe Machinery Corporation, New
York, N. Y., a corporation of Delaware

Application September 2, 1937, Serial No. 162,131

8 Claims. (Cl. 12—36)

This invention relates to presses for use in attaching shoe elements together characterized by an inflatable pressure applying pad, and, more particularly, to means for conducting inflating fluid to the pad.

A general object of the invention is the provision in a shoe press having an inflatable pad of fluid conducting means which permits ready and rapid mounting and demounting of the pad without necessitating disturbance of associated structure, is simple in construction and capable of being economically manufactured and assembled.

A more specific object of the invention is the provision in such a press of inflating fluid conduit structure which permits easy removal or replacement of the pad by simple manipulation of a single anchoring device without disturbing portions of the conduit structure such as a valve connection.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawing, in which:

Fig. 1 is an elevational view with parts in section and broken away of a shoe press showing an embodiment of the present invention;

Fig. 2 is an enlarged, detailed view with parts in section and broken away of the inflating fluid conduit structure shown in Fig. 1; and

Fig. 3 is a transverse sectional view through the conduit structure taken substantially on line 3—3 of Fig. 2.

Prior to the present invention, it has been a practice to assemble shoe elements with suitable cement therebetween in a shoe press adapted to place them under pressure while the cement is setting. Such a shoe press commonly includes an inflatable pressure pad mounted upon the press frame and provided with an inflating fluid conduit. In known types of such presses the conduit extends to the rear of the press and terminates in a valve connection adapted to being engaged by an inflating chuck. The usual pad consists of a rubber bladder surrounded by a casing of suitable material such as leather. A com-

mon form of inflating conduit for the pad comprises a stem extending therefrom and through an opening in the press base of the press frame and is provided near its base with external threads for engagement by a nut to secure the 5 pad in position on the press frame. Beyond the threaded base the stem is bent substantially at right angles and the end thereof is engaged by a sleeve projecting through an opening in a depending portion on the rear of the base of the 10 press frame. The sleeve at its outer end is internally threaded to receive a valve structure comprising a valve seat and a spring biased valve normally seated there against and associated with a plunger for unseating the same. In order to 15 assemble the structure the valve stem must be guided through the opening in the press frame and secured in position with the nut. The sleeve is then projected through the opening in the depending portion and the end thereof is threaded 20 upon the end of the stem. To demount or replace the pad it is thus necessary to remove the sleeve carrying the valve and then the nut engaging the stem.

This entails considerable labor and necessitates removal or disturbance of the entire conduit structure. The structure of the present invention eliminates the necessity of following the above procedure and avoids the difficulties attendant thereon. Assembling, removal or replacement of the pad requires merely a simple manipulation of a single anchoring device without necessitating disturbance of the valve connection, the conduit structure being made in parts in a manner whereby the pad and associated stem may be quickly and easily mounted upon and demounted from the press frame without disturbing the valve and conduit structure associated therewith.

The embodiment of the invention shown in 40 the drawing comprises a press frame base member 10 recessed to receive an inflatable pressure pad 11 comprising a rubber bladder 12 adapted to be inflated and deflated and a casing 13 of suitable material such as leather. The inflatable 45 pad constitutes a work engaging face which is yieldable and capable of applying pressure to work held thereagainst. The press frame includes a bow member 14 having toe and heel posts 15 and 16 constituting abutment means to 50 hold a shoe or lasted upper (not shown) on a last 17 against upward movement. For convenience of access to the valve inflating conduit, particularly when such a press is to be used with a carrier or continuous conveyor of known type, 55

the inflating conduit terminates at the rear of the base member 10 in a valve structure 18 provided with a projecting plunger 19 for unseating the valve. The press shown in the drawing is depicted only by way of example, since the present invention may be used with equal advantage with any type of shoe press provided with an inflatable pad such as a flat platen press of the type disclosed in my copending application, Serial No. 10 138,735 filed April 24, 1937.

The base member 10 is provided on the bottom thereof with a depending web 20 terminating in a boss 21 having an opening 22 extending therethrough to the inner side of the base member. A conduit 23 communicates with the opening 22 at a point within the wall or boss as shown, and may comprise a bore extending from a threaded valve receiving socket 24 or if desired, particularly when the base casting is porous as is frequently the case in mass production, a tube located in such a bore having its outer end adapted to receive a gasket to provide an air tight connection with the end of the valve structure 18.

25 The pad bladder 12 is provided with a stem 25 comprising a hollow throat member having an aperture 26 leading to its interior adapted when the stem is in position in the opening 22 to communicate with the conduit 23. The stem or throat member 25 may comprise a thimble having means such as a flange on its inner end engageable against an interior wall of the pad and a threaded outer end projected beyond the press frame wall and engaged by a fluid-tight cap to close the outer end of the thimble and seal the ends of the wall opening 22.

In the preferred form the stem 25 comprises a stay bolt having its head 26 engageable against an interior wall of the bladder 12 and its outer end 27 extending beyond the press frame wall or boss 21 and threaded to receive a cap or nut 28 and a sealing gasket 29. A rubber gasket 30 is preferably placed between the bladder 12 and the inner side of the press frame wall adjacent the inner end of the opening 22. When the nut 28 is tightened the inner and outer ends of the opening 22 are efficiently sealed by the gaskets 30 and 29. The stay bolt 25 is provided with an axial bore 31 communicating with the interior of the bladder 12 and extending short of its outer end 27. The conduit 23 communicates through aperture 26 with the bore 31. The passage provided by the stem 25 between conduit 23 and the interior of the bladder 12 may be formed in any suitable alternative manner, such as by a channel in the exterior surface of the stem 25 communicating between the conduit 23 and the interior of the bladder 12 by means of a hole in the stem head 26.

60 To prevent rotation of the stem 25 in the opening 22 the former is preferably provided with a rectangular section and the opening 22 is similarly shaped to receive it as is more clearly shown in Fig. 3. It is to be understood, however, that any suitable alternative means may be used for this purpose, such as fins seating in grooves in the wall of the opening 22, keys and keyways or any other desired angularly shaped section.

70 It will thus be seen that the objects set forth above are efficiently obtained. Preferably, the conduit 23 is mounted on or formed in the frame 10 and the valve structure is mounted in the outer end thereof. The pressure pad is then easily and 75 readily mounted by inserting the stem 25 in the

opening 22 and applying the nut or cap 28 to the projecting threaded end 27. Thus the pad may be readily removed without disturbing the remainder of the conduit structure by removing the nut or cap 28 and withdrawing the stem 25 from the opening 22.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a press having a pad carrying frame and an inflatable pressure pad carried thereby, the combination comprising, a press frame wall adjacent said pad and having an opening therethrough, a hollow throat member in said opening having an open end communicating with the interior of said pad, said press having a conduit communicating with said wall opening, said throat member having an aperture leading to its interior and located in said wall opening in position to receive fluid from said conduit, a flange on the inner end of said throat member overlying the interior wall of said pad, a gasket surrounding said throat member between said pad and press wall, an outer gasket surrounding said throat member adjacent the outer side of said press wall, and a single tightening nut threadable over the outer end of said throat member to tighten both said gaskets in sealing relation at the ends of said press wall opening.

2. In a press having a pad carrying frame and an inflatable pressure pad carried thereby, the combination comprising, a press frame wall adjacent said pad and having an opening therethrough, a hollow throat member in said opening having an open end communicating with the interior of said pad, said press having a conduit communicating with said wall opening at a point within said wall, said throat member having an aperture leading to its interior portion and located in said wall opening in position to receive fluid from said conduit, means sealing the inner end of said wall opening around said throat member, and means including a fluid-tight cap sealing the outer end of said wall opening.

3. In a press having a pad carrying frame and an inflatable pressure pad carried thereby, the combination comprising, a press frame wall adjacent said pad and having an opening therethrough, a hollow throat member extending through said opening and having an open end communicating with the interior of said pad, said press having a conduit communicating with said wall opening at a point within said wall, said throat member having an aperture leading to its interior and located in said wall opening in position to receive fluid from said conduit, a flange on the inner end of said throat member engageable against an interior pad wall, the outer end of said throat member being threaded and projected beyond said press frame wall, and a nut threadedly engaging the projecting end of said throat member and sealing the outer end

of said wall opening, said nut serving also to tighten said flange to the press wall to seal the inner end of said wall opening.

4. In a press having a pad carrying frame and an inflatable pressure pad carried thereby, the combination comprising, a press frame wall adjacent said pad and having an opening therethrough, a hollow throat member in said opening having an open end communicating with the interior of said pad, said press having a conduit communicating with said wall opening at a point within said wall, said throat member having an aperture leading to its interior portion and located in said wall opening in position to receive fluid from said conduit, means to prevent rotation of said throat member, means sealing the inner end of said wall opening around said throat member, and means including a fluid-tight cap sealing the outer end of said wall opening.
5. In a press having a pad carrying frame and an inflatable pressure pad carried thereby, the combination comprising, a press frame wall adjacent said pad and having an opening therethrough, a fluid-supplying conduit communicating with said opening at a point within said wall, a stay bolt extending through said opening with the head thereof engageable against an interior pad wall and the outer end thereof being threaded and extending beyond said press frame wall, and means threadably engaging the projecting end of said bolt in a manner to seal the inner and outer ends of said wall opening, said stay bolt having a longitudinally extending passage communicating with the interior of said pad and said conduit.
6. In a press having a pad carrying frame and an inflatable pressure pad carried thereby, the combination comprising, a press frame wall adjacent said pad and having an opening therethrough, a fluid-supplying conduit communicating with said opening at a point within said wall, a stay bolt extending through said opening with the head thereof engageable against an interior pad wall and the outer end thereof being thread-

ed and extending beyond said press frame wall, said stay bolt having an angularly shaped section cooperating with a similarly shaped section of said wall opening to prevent rotation of the former, and means threadably engaging the projecting end of said bolt in a manner to seal the inner and outer ends of said wall opening, said stay bolt having a longitudinally extending passage communicating with the interior of said pad and said conduit.

7. In a press having a pad carrying frame and an inflatable pressure pad carried thereby, the combination comprising, a press frame wall adjacent said pad and having an opening therethrough, a fluid-supplying conduit communicating with said opening at a point within said wall, a stay bolt extending through said opening with the head thereof engageable against an interior pad wall and the outer end thereof being threaded and extending beyond said press frame wall, and a fluid-tight thimble threadably engaging the projecting end of said bolt in a manner to seal the inner and outer ends of said wall opening, said stay bolt having a longitudinal bore communicating with the interior of said pad and extending short of the outer end and an aperture communicating between the bore and said conduit.

8. In a press having a pad carrying frame and an inflatable pressure pad carried thereby, the combination comprising, a press frame wall adjacent said pad and having an opening therethrough, a fluid-supplying conduit communicating with said opening at a point within said wall, a stem in said opening having an open end communicating with the interior of said pad and an outer end threaded and extending beyond said press frame wall, means threadably engaging the projecting end of said stem whereby the inner and outer ends of said wall opening are sealed when said means is tightened, and a passage communicating between the interior of said pad and said conduit provided by said stem.

JOHN FREDERICK SMITH.
